UNITED STATES PATENT OFFICE.

ULYSSES G. MCQUEEN, OF NEW YORK, N. Y.

DESIGN FOR A WINDOW-PULLEY BRACKET.

SPECIFICATION forming part of Design No. 34,999, dated August 27, 1901.

Application filed July 26, 1901. Serial No. 69,858. Term of patent 14 years.

To all whom it may concern:

Be it known that I, ULYSSES G. MCQUEEN, a citizen of the United States, residing at No. 686 East One Hundred and Thirty-eighth street, in the borough of Bronx, city, county, and State of New York, have invented and produced a new and original Design for a Window-Pulley Bracket, of which the following is a specification, reference being had to the accompanying drawings, forming part thereof.

The design which is the subject-matter of the present application consists of a new and original configuration for window-pulley brackets.

The design is illustrated in the accompanying drawing, in which a window-bracket embodying it is shown in perspective.

1 designates an extended shank or base plate bearing at one end and integral with it 20 a hood 2. This hood is substantially the shape of a hollow disk having its circumference rounded, as indicated at 3. A portion of the disk is cut away, so as to form the arc-shaped recess 4. Also the base of the plate 1 is 25 stepped, so as to form the recesses 5. Located centrally of the disk are the round apertures 6.

What is claimed as new is—

The design for a window-pulley bracket, 30 substantially as shown and described.

ULYSSES G. MCQUEEN.
